UNITED STATES PATENT OFFICE.

FRANK W. DANIEL, OF WISSINOMING, PENNSYLVANIA, ASSIGNOR TO QUAKER CITY RUBBER COMPANY, OF PHILADELPHIA, PENNSYLVANIA, A CORPORATION OF PENNSYLVANIA.

DESIGN FOR A TIRE TREAD.

Application filed August 12, 1922. Serial No. 3,367. Term of patent 14 years.

To all whom it may concern:

Be it known that I, FRANK W. DANIEL, a citizen of the United States, residing at Wissinoming, in the county of Philadelphia and State of Pennsylvania, have invented a new, original, and ornamental Design for Tire Treads, of which the following is a specification, reference being had to the accompanying drawing, forming a part thereof.

The figure is a perspective view of a tire showing my new design.

I claim:

The ornamental design for a tire tread as shown.

In testimony whereof I have hereunto set my hand, this 11th day of August, 1922.

FRANK W. DANIEL.
